AIR SEPARATOR

Thomas J. Sturtevant, Wellesley, Mass., assignor
to Sturtevant Mill Company, Boston, Mass., a
corporation of Massachusetts

Application March 27, 1931, Serial No. 525,654

13 Claims. (Cl. 209—139)

This invention relates to air separators for grading materials of the type disclosed in Letters Patent of the United States No. 1,615,558 dated January 25, 1927 and 1,703,833 dated February 26, 1929 as improved by features disclosed in Letters Patent of the United States No. 1,788,361 dated January 6, 1931.

The principal object of this invention is to improve the selective action of the separator within the inner drum or separating chamber. To this end a feature of the invention resides in the provision of means, which may effectively be in the form of a rotary member, acting within the upper portion of the zone of the selective action of the air currents within the separating chamber and so constructed and arranged as to increase the centrifugal effect.

The entire zone of the selective action in the separating chamber extends from where the air, moving in a closed circuit, enters at the bottom and leaves through the centralized outlet in the head of the drum. The motion of the upward current of air is in the form of a spiral or whirlwind due to the rotating parts in the separating chamber and to the fan above. The material to be separated is centrifugally distributed into this rising current of air and is acted on by three forces, the upward action of the air current, the outward action of centrifugal force and the downward action of gravity. The resultant of these forces determines the largest particle size that passes up through the outlet on its way to the surrounding settling or collecting chamber. The outward action of centrifugal force is highly important and for best results should be as uniform as possible. This centrifugal action tends to collect the material against the wall of the drum which forms the separating chamber, in a more or less compacted whirling layer which tends to move downward under the influence of gravity and upward due to the rising air current, but because the outlet from the separating chamber always is smaller than the maximum diameter of the chamber, a whirling particle must be moved inward by the air current, against the centrifugal forces generated, in order to pass over into the collecting chamber. While separation takes place more or less in all parts of the separating chamber the zone close to the upper outlet is the more important, as there the air current has to move the particles of material against gravity and in addition against centrifugal forces generated by the distributor. It follows from the above that for fine and uniform work in a separator, there should be a maximum

of centrifugal effect in the zone close to the outlet of the separating chamber where the particles of material have to move inwardly to escape from the separating chamber. For close selection provision should be made, as far as possible, to have all of the particles of material acted on uniformly. The particular object of this invention is to insure a maximum of centrifugal effect within that part of the zone of the selective action where it is required for fine and uniform work.

To the accomplishment of this object and such others as may hereinafter appear, as will readily be understood by those skilled in the art, the invention comprises the features and combinations of parts hereinafter described and then particularly pointed out in the appended claims.

The nature and scope of the invention will be understood from a description of the preferred embodiment thereof illustrated in the accompanying drawings, in which:

Figure 1 is a view, in vertical section, through an air separator of the whirlwind type provided with a centrifugal agitator in the zone of separation close to the outlet from the separating chamber;

Fig. 2 is a view, in plan of the rotary centrifugal agitator, and in section through the wall of the drum which forms the separating chamber;

Fig. 3 is a view, in perspective, of the preferred form and the manner of mounting an agitator blade; and

Figs. 4 and 5 show perspective views of modified forms of the agitator blades.

Referring to the drawings, the separator shown therein as an illustrative embodiment of the invention comprises an outer casing 1 consisting of a drum having a cylindrical wall 3 closed by a flat head 5, and having a cone 7 at the lower end thereof terminating in a discharge spout 9. Within and spaced from the outer casing is an inner casing or drum 11 consisting of a cylindrical wall 13 closed by a flat head 15 with a centralized outlet opening 17 therein, and having a conical shell 19 at the lower end thereof. This inner casing is supported by brackets 21 between and secured to the walls 3 and 13.

Beneath and spaced from the conical shell 19 is a cone 23 provided with a discharge spout 25 which extends laterally through an opening in the cone 7 of the outer casing. The cone 23 is supported by plate struts 27 between and secured to it and the cone 7.

The inner casing forms the separating chamber 33, and the annular space between the inner

and outer casing walls 3 and 13 forms the settling or collecting chamber 35. The space between the conical shell 19 and the cone 23 serves as an inlet opening for the passage of air from the settling chamber back into the separating chamber. Located at this space is a series of adjustable vanes 37 pivotally connected to a ring 41 secured to and projecting outward from the lower edge of the conical shell 19 and adjusted by a hand wheel 49 all substantially as described in said Patent No. 1,788,361 referred to.

To vary the outlet opening 17 in the head of the inner casing, a valve may be provided comprising a series of overlapped plates 51 resting upon the head of the inner casing and connected to radial bars or handles 53 which extend outward through brackets 55 secured to the outer casing. These handles may be adjusted exteriorly of the outer casing in order to vary the size of the opening. This valve may be similar to that disclosed in said patent No. 1,615,558 referred to.

The materials to be graded are conducted into the separating chamber through an inclined delivery chute 57 and through a conical feed hopper 59 depending from the head 5 and having a lower cylindrical neck 60 extending down through the outlet opening in the head 15 of the separating chamber. Mounted on the head of the outer casing are a pair of channels 61 supporting a housing 63 which extends downward through the head 5 into the hopper 59 and has bearings in the upper and lower ends thereof. A vertical driven shaft 65 is journaled in said bearings, and within the portion of the housing above the head 5 has a bevel gear 67 fast thereon meshing with a bevel pinion 69 on a horizontal driving shaft 71 journaled in an inner bearing carried by the housing 63 and in an outer bearing 73 carried by a transverse channel 75 bridging the channels 61. At the outer end of the driving shaft 71 is a pulley 77 which may be driven from any suitable source of power.

The driven shaft 65 extends down from the bearing housing centrally of the feed hopper 59-60, its lower end projecting therefrom into the separating chamber 33. This lower end carries a distributor 79 comprising a plate hub 81 and a plurality of downwardly flanged segmental plates 83, secured to the plate hub and to each other, as is well known in this type of air separator.

Projecting up from the margin of the distributor plate hub 81 are posts 89 carrying a cylindrical hub 91 surrounding the cylindrical neck 60 of the feed hopper and provided with a lower horizontal flange 93 and an upper cone flange 95. Secured to the cone flange 95 are a plurality of oblique arms 97 each carrying a fan blade 99. The fan rotates clockwise in a chamber 101 between the casing heads 5 and 15, and its blades may overlap the upper, open end of the settling chamber.

The distributor 79 is provided, as usual in this type of separator, with a circular cover or baffle plate which may be substantially of the diameter of the distributor 79. In the present instance this conveniently is formed of four segmental sections 103 (Fig. 2) overlapped and bolted at their radial meeting edges and also screwed to the lower flange 93 of the cylindrical hub 91. In the whirlwind type of air separator illustrated the baffle thus constructed is below and relatively close to the fines outlet 17, that

is, it is in the upper rather than in the lower part of the zone of the selective action or classification within the separating chamber 33.

In the operation of an air separator constructed as hereinbefore described the materials to be graded are fed to the distributor hub plate and are whirled and thrown outward therefrom under the influence of centrifugal force, the heavier particles tending to be thrown outward against the wall of the separating chamber through the rising air currents and the lighter particles or fines being carried upward around the distributor baffle and thence inward through the outlet and over into the settling chamber. As the upward whirling air current lifts the material in suspension into the upper zone of the separating chamber and toward its outlet, centrifugal force and gravity act to prevent particles larger than those desired from passing through the outlet. The fines raised to the upper part of the classification zone, or to the outer portion of the separating chamber, must then travel inward to escape through the outlet. If the centrifugal action in this upper zone close to the outlet is increased then, the fineness of separation remaining constant, a corresponding increase in the power of the rising air current is established to carry only the suspended fines through the outlet, the larger particles being impelled in an opposite direction, or away from the outlet, to the wall of the separating chamber where they may fall to be discharged through the spout 25.

To accomplish these desired results the distributor baffle, itself being in the upper part of the classification zone, is utilized as a support or carrier for the novel means now to be described for increasing the centrifugal action above the baffle and at the same time preventing the larger particles thus carried outward from short-circuiting to the outlet for the fines.

Bolted on the upper side of the distributor baffle and extending outward well into the upper classification zone, are a plurality of agitator blades 105, eight being shown in Fig. 2. The height of these blades is such that the plane of their upper surfaces is close to the outlet for the fines. The blades are so proportioned and set that the clearance between them and the cover of the separating chamber and between their ends and wall of the separating chamber is such that their rotation carries them across the path of the air current as it turns to pass out of the cover outlet. In their preferred mounting they are set to slant backward from a radial position in relation to the direction of rotation. This is not essential but some increase in the ease of travel of particles impelled outward is observed, and when so mounted damp material has more difficulty in sticking to the forward faces of the blades.

An important characteristic of the agitator blades comprises a shelf, conveniently a flange 107, at the top edge projecting in the direction of rotation. As the blades move through the air current the heavier particles are engaged and impelled outward and the forwardly facing, overhanging shelf along the top edge of each blade prevents any particles moving diagonally across the blades from passing over the top edge and thus to the fines outlet. The flanges stop the upward movement and translate it into outward movement. Thus the classification zone close to the outlet from the separator chamber, through which the suspended fines must move inward to escape, has the heavier particles hurled outward through it with greatly increased centrifugal

force with the result that the selective action is greatly improved.

Referring to Fig. 3 the preferred form of the agitator blades 105 may readily be made by removing a portion of one flange of a channel iron. This leaves a complete flange 107 along the top edge and a partial flange 108 at the inner or supported end of the bottom edge. This end is punched and utilized to bolt the blade to the baffle plate 103.

When not so fine a product is desired the centrifugal effect may be diminished by reversing the blades which places the flanges at the bottom edge and turns them backward thus permitting some of the impacted particles to travel diagonally across the blades because not held back so strongly by centrifugal force. To readily permit such a reversal of position the inner portions of the flanges 107 are punched in alignment with the lower flange punchings so that either set of punchings may receive the holding bolts.

Those skilled in the art will understand that the blade or centrifugal agitator may be of any form that will tend to prevent particles from crossing the blade easily or will constrain the particles that impact against the face to pass off at the outer end, thus subjecting the particles to a maximum centrifugal effect as the outer end of the blade travels faster than any other portion. Thus good results have been obtained with centrifugal agitators in the form of a channel 103 as illustrated by Fig. 4, or with narrower channels 110 built up to the maximum height permitted by the available space and bolted together through their engaged flanges, as illustrated by Fig. 5. Such a sectional centrifugal agitator permits variation of its effective surface according to the fineness of classification that is desired. It will be observed that each of these modified blades may be bolted to the baffle in a reverse position.

The nature and scope of the present invention having been indicated and its preferred embodiments having been specifically described, what is claimed as new, is:—

1. A centrifugal agitator blade for air separators shaped to a channel section for one portion of its length and to an angle section for the remaining portion of its length.

2. A centrifugal agitator blade according to claim 1 having aligned bolt holes in the two flanges of its channel section portion for bolting in the same position either edge up.

3. An air separator of the type described comprising a rotary distributor plate and a rotary baffle therefor within a covered casing forming a classification zone, said casing having a centralized top opening, and a series of blades mounted on said baffle each consisting of a plurality of channel irons detachably secured flange to flange so that each blade has one flat face and one flanged face, said blades being mounted with their flanged faces forward in the direction of rotation, the height of the blade being such that the upper channel iron substantially sweeps said top opening, and the detachability of said channel irons permitting removal of one or more to space the blades further from said top opening and vary the selective action.

4. In an air separator of the type described the combination with a covered casing which defines a zone of classification having a centralized top opening and a bottom opening, a valve for varying the effective area of said top opening, means for causing an air current to flow upward through

said openings, adjustable vanes at said bottom opening, means for distributing the material to be classified centrifugally into said zone, and a rotary device comprising a series of upstanding blades above the distributor and close to said top opening each individual blade having a shelf along its upper edge against which impacted particles engage and are caused to pass off the outer end of the blade with increased centrifugal force.

5. In an air separator of the type described, the combination with a covered casing which defines the zone of classification having a centralized outlet through its cover, means for causing an air current to flow upward within said casing and through said outlet and rotary means for distributing the material to be classified centrifugally into said rising air current, of a rotary device for increasing the centrifugal effect within the upper part of said zone comprising a plurality of blades each flanged at its upper edge and each being set vertically with its flange directed forward whereby the impacted heavier particles crossing said blades from bottom to top and tending to short-circuit through said outlet are intercepted by said flanges and directed outward.

6. In an air separator of the type described, the combination with a covered casing which defines the zone of classification having a centralized outlet through its cover, means for causing an air current to flow upward within said casing and through said outlet and rotary means for distributing the material to be classified centrifugally into said rising air current, of a rotary device located just below said outlet and its surrounding cover comprising a support below said outlet and a plurality of vertically mounted blades each having an inner portion secured to said support and underlying said outlet and an outer portion extending freely beyond said support and underlying said cover, there being a lateral projection at the top edge of each blade at its inner supported portion at least to intercept the upwardly rising heavier particles below said outlet and direct them outward away from said outlet and beneath said cover.

7. In a separator of the type described, the combination with a fan for causing air currents to flow upward through the top opening of an underlying classification zone and a rotary distributing plate within said zone, of a rotary centrifugal agitator between the distributing plate and fan comprising a circular series of vertically mounted blades each having a flange along its top edge overhanging its forward face.

8. The invention described by claim 7 in which each blade of the series is mounted to slant backward from a radial position in relation to the direction of rotation.

9. The invention described by claim 7 in which a rotary baffle is located within said zone above the distributing plate, and the blades of the centrifugal agitator are mounted on said baffle.

10. In a separator of the type described having a central classification zone, the combination with a rotary distributor and overlying baffle therefor in said zone, of a plurality of spaced agitator blades mounted on said baffle projecting individually from said baffle well into the portion of said zone surrounding the baffle, each such blade slanting backward from a radial position in relation to the direction of rotation and having its top edge bent forward in the direction of rotation

to prevent impacted particles from crossing the blade.

11. An air separator of the type described having a rotary shaft within the separating chamber, 5 a distributor including a baffle plate rotated by said shaft, and a centrifugal agitator comprising a circular series of blades mounted vertically on the upper side of said baffle plate each said blade having a flange at each longitudinal edge both 10 overhanging the same side of the blade and punchings in both flanges at one end of the blade to provide for mounting the blade vertically either edge up.

12. An air separator of the type described having a rotary shaft within the separating chamber, 15 a distributor including a baffle plate rotated by said shaft, and a centrifugal agitator comprising a circular series of blades mounted vertically on the upper side of said baffle plate each said 20 blade comprising a plurality of channel irons built up vertically and secured together flange

to flange forming a unitary blade having one flat face and one multiple flanged face.

13. In an air separator of the type described the combination with a cylindrical casing defining a separating chamber, a circulating fan outside said 5 casing to cause air currents to flow upward through said zone and through a centralized outlet in the casing top, a rotary distributor within said casing and a baffle plate above said distributor defining a classification zone between it and 10 the casing top, of a rotary centrifugal agitator comprising a series of blades mounted on the upper side of said baffle, said agitator having the plane of its upper surface close to said outlet and each of said blades extending across the edge of 15 said outlet into the path of the air current as it turns inward under said casing top to pass out of said outlet and slanting backward with reference to its direction of rotation from a position on a radius of said cylindrical casing.

THOMAS J. STURTEVANT.
